JUVENILE TRUCK

Carter E. Quisenberry, Kirkwood, N. Y., assignor to American Machine and Foundry Company, a corporation of New Jersey

Application October 29, 1956, Serial No. 43,551

Term of patent 14 years

(Cl. D34—15)

The single figure is a perspective view of a juvenile truck, showing my new design, the opposite side being substantially a mirror image thereof.

The dominant features of my new design are shown in solid lines in the drawing.

I claim:

The ornamental design for a juvenile truck, as shown and described.
